METHOD AND MECHANISM FOR DELIVERING AND STACKING SHEETS.

Application filed April 8, 1924. Serial No. 704,963.

The invention relates to a novel method and mechanism for delivering and stacking sheets coming from a printing press or other mechanisms for operating thereon.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation, partly diagrammatic, of a mechanism embodying the invention;

Fig. 2 is a top plan corresponding to Fig. 1;

Fig. 3 is an enlarged, fragmentary elevation looking at Fig. 2 from the bottom of the figure;

Fig. 4 is a longitudinal section taken on line 4—4 of Fig. 2;

Fig. 5 is an enlarged, fragmentary detail section, taken on line 5—5 of Fig. 2;

Fig. 6 is an enlarged, fragmentary plan, corresponding to Fig. 2 but with the feed board removed.

The invention as herewith illustrated is shown embodied with a printing press of the bed and cylinder type, and as delivering the sheets from the impression cylinder and stacking them. It will be understood, however, that the invention is applicable in other constructions and in other relations for delivering and stacking sheets.

Referring now in detail to this embodiment of the invention, illustrated by way of example in the accompanying drawings, the frame 1 (Fig. 1) of the printing press supports the bearings 2 of the impression cylinder 3, these parts being shown largely in a conventional manner. The cylinder 3 is driven by a train of gears 4, 5, 6 and 7 from the shaft 8. The sheets are fed to the cyl-

inder 3 from a feed-board 9 and are printed upon by a flat bed not shown.

Referring now to the delivery mechanism, it is preferably of the hinged type, although the invention in its main features is applicable equally to other types of delivery mechanism. The frame of the main body of the delivery table (Figs. 2, 3 and 6) comprises a table proper 19 in one or more longitudinal parts, and side rods 20 and 21, extending longitudinally of the press, the side frames of which are shown at 22 and 23. It will be understood that the term table as broadly used comprises any means for supporting a sheet while it is being progressed. Cross rods 24 and 25 extend between, and are connected to, the longitudinal rods 20 and 21, and constitute therewith the main frame.

In the embodied form of hinged mounting the rear ends of the rods 20 and 21 are fixed, respectively, in hollow lugs 28 and 29, which lugs are rotatably supported in frame pieces 30 and 31, mounted upon the press frame just above the bearings for the impression cylinder. The rotatable mounting of the lugs 28 and 29 in the frame permit the hinged raising and lowering of the delivery table.

Means are provided by the invention for positively progressing the delivered sheets after they have passed to the delivery table from the impression cylinder, and as embodied, this means comprises traveling suction devices engaging with the underside of the sheet, that is, the non-printed side thereof, and the freshly printed side is kept free from any harmful contact whatsoever. As embodied (Figs. 2, 3 and 6), a shaft 34 passes loosely through the hollow lugs 28 and 29, and is journaled in the frame at either side thereof.

Fixed on shaft 34 is a roller 35, to rotate therewith, and stripping and supporting fingers 36 carry the lead edge of the sheet from the impression cylinder 3 on to the delivery table. Portions of the roller 35 are formed to constitute driving rollers for suction and forwarding belts 39 and 40. Shaft 34 is driven in any suitable manner, as by a pinion 41 on one end of the shaft, meshing with a gear-wheel 42, which is driven from the general gearing of the press.

The tapes 39 and 40 at their forward ends (Figs. 2, 4 and 6) run over idle pulleys 48 and 49, respectively, which are mounted for longitudinal adjustment or positioning on the frame, to take up any slack in the belts. As embodied, (Figs. 1 and 6) the rollers 48 and 49, respectively, are carried on stub shafts 50 mounted in blocks 51. Each block 51 has a bar 52 extending laterally therefrom, each bar having therein a slot 53. A bolt 54 passes through the slot 53 and is screwed into a block 55 carried on the tying rod 25 of the frame.

The suction-effecting means (Figs. 2, 4 and 5) as embodied, comprises a series of perforations 60 in the respective belts 39 and 40, these perforations being disposed along the belts and preferably spaced relatively closely together. Beneath each belt, 20 in close friction contact therewith, and extending preferably the entire length thereof, that is, from roller to roller is an air-chamber 62 for belt 39, and a like chamber 63 for belt 40. In the upper flat face of each 25 air chamber, that is, the face upon which the belt slides in close friction contact, there is formed a longitudinally-extending recess 64 and 65, respectively.

At relatively widely-spaced intervals, an 30 air-suction opening 66 communicates from the interior of the suction chamber 62 into the groove 64 in one case, and from air-chamber 63 into groove 65 in the other case. Suitable means for exhausting the air to 35 effect suction through the forwarding belts are provided, such as a fan or other suitable device, and an air pipe 69, having communication with the bottom part of the suction chambers 62 and 63, through apertures 70, 40 communicates with said air suction means.

It will thus be seen that as soon as the lead end of the sheet is delivered from the impression cylinder, it is subjected to very gentle but positive holding suction at a plurality 45 of points transversely, and is immediately positively propelled forward at the surface speed of the impression cylinder, the gentle suction holding means acting preferably at a plurality of relatively closely 50 located points along the sheet throughout the entire length thereof as it progresses along the delivery table. It will be understood that while two cooperating belts are shown, side by side, that a larger number 55 may be employed as found desirable or suitable, and the belts may also be adjustable or positionable transversely of the delivery table.

Means are provided for delivering the 60 sheet with a downward direction, and preferably deflection of the forward end of the delivery table, and also with a transverse and outwardly and upwardly curving or dishing of the sheet. Due to the above-described curvature, the sheet will feed out

symmetrically and rigidly for its entire length, and due also to the downward deflection, there will be no rolling or folding of the forward end of the sheet, and it will settle symmetrically and uniformly on the 70 stack of delivered sheets. The invention provides also for acting upon the sheets by the suction progressing means during this deflection and transverse curving of the feed in delivering. This latter action also 75 contributes to the symmetrical and exactly uniform delivery of the sheets onto the stack.

As embodied (Figs. 2, 3 and 6), the front 80 end of the delivery table is downwardly inclined as already described, and is longitudinally variably positionable relatively to the main delivery table, to vary the length of this downwardly inclined portion relatively to the main part of the delivery table, 85 and thereby positioning the forward end of the delivery relatively to the stack of delivered sheets. As embodied, this inclined, forward portion comprises longitudinally-extending side rods 84 and 85, having at the 90 rear end thereof a hollow, transversely-extending tie rod 86. The ends of the rods 84 and 86 are fixedly mounted in a block 88, which is mounted upon rod 20 of the main 95 delivery table to slide longitudinally thereof. At the opposite side of the machine, rods 85 and 86 are fixedly mounted in a block 90, which is likewise mounted on side rod 21 of the main frame to slide longitudinally thereof. 100

Near its forward end, the inclined portion of the feeding table (Figs. 2 and 6) has a cross rod 92, fixed to lugs 93 and 94, respectively, which lugs are slidably, respectively, upon the side rods 20 and 21 of the main 105 delivery table. The side rods 84 and 85 of the inclined forward part of the delivery table are slidably mounted in apertures in the lugs 93 and 94.

The positioning means for the inclined 110 table (Figs. 2, 3 and 6) comprises straight racks 97 and 98, formed on the underside of the respective side rods 20 and 21 of the main frame. Meshing with these straight gear racks, respectively, are pinions 99 and 100, 115 fixed on a transversely-extending shaft 101, which shaft is journaled within the hollow rod 86 (which is the end rod of the inclined delivery table). At one end the shaft 101 is provided with a hand-wheel 102. By 120 rotating the hand-wheel 102, blocks 88 and 90 slide along the side rods 20 and 21 of the main delivery table, and the side rods 84 and 85 of the inclined delivery table slide with the lugs 93 and 94. The inclined table is 125 thereby either lengthened or shortened relatively to the main delivery table, and the forward end of the delivery means is likewise positioned as desired relatively to the stack 130 of sheets on the stacking mechanism, this

latter positioning or adjustment depending on the size of the sheets being delivered and stacked.

In the preferred form of the invention, 5 the inclined delivery table is likewise provided with the suction sheet-progressing devices (Figs. 2 and 6), and in the embodied form these are the same or similar to those previously described. As embodied, two 10 belts 120 and 121, having preferably a relatively large number of closely spaced together suction perforations 122 or 123, respectively, run over pulleys 124 and 125, formed in or mounted on a roller 126. 15 Roller 126 is fixed to a shaft 127, which is journaled in bearings 128 and 129 carried on the forward ends of side rods 84 and 85 of the inclined delivery table.

The belts 120 and 121 at their rearward 20 ends run, respectively, over idle pulleys 133 and 134 (Figs. 1, 4 and 6), which pulleys are indirectly mounted upon rod 86, and are adjustable to take up slack in the belts. For this purpose each of the pulleys is 25 mounted, respectively, on a stub shaft 136, fixed in a block 137, having on the bottom a laterally-extending bar 138, having an aperture 139 therein. A bolt 140 projects through this aperture, and is screw-threaded 30 into a block 141, carried on shaft 86. The air chambers and other suction devices co-operating with belts 120 and 121 are the same as those for belts 39 and 40, and have the same reference numerals applied thereto 35 primed.

The sets of suction conveying belts on the main delivery table and the inclined delivery table, overlap at their adjacent ends so that each sheet is continuously and uniformly held by the light suction from the moment its lead end enters the rear of the delivery mechanism until its tail end is delivered from the forward end thereof. This arrangement will be clearly understood 45 from the preceding description and from inspection of Figs. 2, 4 and 6.

Driving means for the suction belts are provided, adapted for the changes in relative position of the main and inclined delivery tables. As embodied, a sprocket wheel 50 150 (Figs. 2, 3 and 6) is fixed on shaft 34, and a sprocket chain 151 runs thereover and also about a sprocket wheel 152, mounted on a stub shaft 153, which is fixed to and projects from a block 154, fixed on the rod 20. A guiding sprocket wheel 155 is carried on a stub shaft 156, likewise fixed on rod 20. This sprocket wheel 155 is positioned so that there will be no mechanical interference 55 between the two driving chains due to changes in position of the inclined delivery table.

For driving the belts on the inclined delivery a sprocket wheel 160 is mounted on a stub shaft 161, which shaft is supported 60 in the block 88 of the inclined delivery table,

and is slideable on the main delivery table. A sprocket wheel 164 is fixed to rotate with the sprocket wheel 160, and a sprocket chain 165 runs thereover and over a sprocket wheel 166, fixed on shaft 127, already described. 70 It will be seen that during the relative movement of the two parts of the delivery mechanism, sprocket wheel 160 will roll on sprocket chain 151, while remaining in driving mesh therewith, the drive thus accommodating itself to all positions of the delivery mechanism. 75

As previously indicated, means are provided for transversely curving the sheet to maintain it symmetrical and sufficiently 80 rigid during delivery. The curving is from the central part of the sheet outwardly, and preferably also upwardly. Of course, the sheet could be bent otherwise than in the general form of a curve, but this would be 85 an equivalent and usually would prove less efficient. The term curving will be understood as including such other forms as give the same effect. This means, as embodied 90 (Figs. 1, 2, 3 and 6) comprises a plurality 95 of fingers 175, spaced apart transversely and extending longitudinally of the front part of the delivery (in this embodiment being the inclined part thereof). These fingers are mounted upon the rod 92, friction tight 100, or preferably, with clamping screws 176, whereby the various fingers may be disposed at various angular positions with respect to the general plane of delivery and with respect to each other. 105

Thus the central ones may be in the plane of the delivery table, and progressing outwardly toward each side, the respective fingers may be progressively inclined upwardly to a greater extent, thereby imparting any 105 desired degree of transverse upward and outward curvature to the sheet. It will be noted that the suction belts 124 and 125 extend between the fingers 175, so that the action of the curving means and of the positive forward feed upon the sheet is concurrent. Means are also provided for maintaining the delivery bed continuous in all relative positions of the front part, and as embodied, a series of fingers 178, spaced 110 apart transversely, and longitudinally disposed, have a mounting on rod 92, which may be offset with the mounting of the fingers 175. The fingers 178 lie in corresponding recesses 179 in the main delivery table, and slide longitudinally in their recesses as the forward end of the table is moved to and fro, and maintain the table continuous even at the farthest forward extension of the forward part of the table. 115 120 125

Referring now to the sheet-stacking mechanism, certain features thereof may be of any suitable or known form, this mechanism being of the type wherein the sheets are delivered to, and alined upon, the top of the 130

stack, the stack being supported upon a table, which table sinks downwardly proportionately to compensate for the increase in the height of a stack as the sheets are delivered thereonto.

This downward feed of the table is indicated generally by screw rods 188 and 189. The stack supporting table, in accordance with one feature of the invention, comprises a main horizontal part 190 and a front part 191 forwardly and downwardly variably inclined. As embodied, a supporting frame 192 is carried on extensions 193 from the nuts 194, which are screw-threaded respectively, on the shafts 188 and 189. The rotation of these shafts determines the vertical position of the table. The part 190 of the table is supported on blocks 195 and 196, resting upon the frame 192. The hinged forward portion of the table is supported upon a block 197, resting in an inclined channelway in the frame 192. The blocks 197 are of different sizes and are interchangeable, so as to vary the degree of inclination of the part 191 of the stack-supporting table. Guides 198, preferably of a usual type, are provided at the front of the stack, and may also be provided at the sides, if desired.

Suitable jogging or alining means acting upon the sheets as they are delivered to the stack are provided, and as embodied, there is one such device at either side of the stack of sheets, and one such device at the rear, the sheets being thereby alined against the guides 198 at the front of the stack.

As embodied, these mechanisms are mounted clear of the stack, the side jogger supporting structures overhanging the stack, and all of the devices being readily adjustable or positionable for sheets of different sizes. The forwardly and downwardly inclined front end of the stacking table prevents any twisting or disturbance of the sheets as the joggers come away therefrom.

The invention in its broader aspects is not limited to the precise forms and mechanism herein shown and described, but the method may be carried out in various ways and changes may be made in the mechanism without departing from the principles of the invention or sacrificing its chief advantages.

I do not herein show or describe the sheet jogging means in detail; as this will form the subject matter of a separate application.

What I claim is:—

1. A sheet delivery mechanism including in combination a delivery table, a perforate belt, and suction means having an open channel extending beneath the belt, the belt running in friction contact with the suction means thereby closing the top of the channel.

2. A sheet delivery mechanism including in combination a delivery table, a perforate

belt, suction means having an open channel extending beneath the belt, the belt running in friction contact with the suction means thereby closing the top of the channel, an air chamber beneath the channel communicating therewith and means for exhausting the air therefrom.

3. A sheet delivery mechanism including in combination a delivery table, a plurality of belts engaging the underside of a sheet, and arranged longitudinally of the table and with their adjacent ends overlapping and suction means acting on the sheet at each belt and with their ends likewise overlapping.

4. A sheet delivery mechanism including in combination a delivery table, a plurality of perforate belts engaging the underside of a sheet, and arranged along the table with their ends overlapping, and an air chamber beneath each belt with their ends likewise overlapping.

5. A sheet delivery mechanism including in combination a main delivery table, a front delivery table inclined downwardly and forwardly relatively thereto, and suction means on each table adapted to engage a sheet and continuously progress it over said tables.

6. A sheet delivery mechanism including in combination a main delivery table, and a front delivery table inclined relatively thereto and adjustable relatively thereto, and sheet progressing means on both tables engaging a sheet underneath, said progressing means overlapping to thereby act continuously on the sheet.

7. A sheet delivery mechanism including in combination a main delivery table, a front delivery table inclined relatively thereto and adjustable relatively thereto, and belts on both tables engaging a sheet underneath, the belts overlapping to thereby act continuously on the sheet.

8. A sheet delivery mechanism including in combination a main delivery table, a front delivery table inclined relatively thereto and adjustable relatively thereto, and belts on both tables engaging a sheet underneath, and suction means acting on the sheet at the belts, the belts overlapping to thereby act continuously on the sheet.

9. A sheet delivery mechanism including in combination a main delivery table, a front delivery table inclined relatively thereto, and belts on both tables engaging a sheet underneath, and suction means acting on the sheet at the belts, the belts and suction means overlapping to thereby act continuously on the sheet.

10. A sheet delivery mechanism including in combination a main delivery table, a front delivery table inclined relatively thereto, and variably longitudinally positionable relatively to the main table.

11. A sheet delivery mechanism including

in combination a main delivery table, a front delivery table inclined downwardly and forwardly relatively thereto, and variably longitudinally positionable relatively to the main table.

12. A sheet delivery mechanism including in combination a main delivery table, a front delivery table inclined downwardly and forwardly relatively thereto, and means engaging a sheet continuously to progress it over both tables, and variably longitudinally positionable relatively to the main table.

13. A sheet delivery mechanism including in combination a main delivery table, a front delivery table inclined relatively thereto, sheet progressing means on both tables engaging a sheet underneath, said progressing means overlapping to thereby act continuously on the sheet, and variably longitudinally positionable relatively to the main table.

14. A sheet delivery mechanism including in combination a main delivery table, a front delivery table inclined relatively thereto, belts on both tables engaging a sheet underneath, the belts overlapping to thereby act continuously on the sheet, and variably longitudinally positionable relatively to the main table.

15. A sheet delivery mechanism including in combination a main delivery table, a front delivery table inclined relatively thereto, and belts on both tables engaging a sheet underneath, and suction means acting on the sheet at the belts, the belts overlapping to thereby act continuously on the sheet, and variably longitudinally positionable relatively to the main table.

16. A sheet delivery mechanism including in combination a delivery table, a plurality of suction means engaging a sheet underneath and progressing it along the table, said means being located along the table and with their ends overlapping, and being relatively variably positionable longitudinally of the table.

17. A sheet delivery mechanism including in combination a delivery table, a plurality of belts engaging the underside of a sheet, and arranged longitudinally of the table and with their adjacent ends overlapping and suction means acting on the sheet at the belts, the belts being relatively variably positionable longitudinally of the table.

18. A sheet delivery mechanism including in combination a delivery table, a plurality of belts engaging the underside of a sheet, and arranged longitudinally of the table and with their adjacent ends overlapping and suction means acting on the sheet at the belts, the belts and suction means being relatively variably positionable longitudinally of the table.

19. A sheet delivery mechanism including in combination a delivery table, a plurality

of perforate belts engaging the underside of a sheet, and arranged along the table with their ends overlapping, and an air chamber beneath each belt; said air chambers having their ends likewise overlapping, the belts and air chamber being relatively variably positionable longitudinally of the table.

20. A sheet delivery mechanism including in combination a delivery table, means for bending the sheet transversely and upwardly and outwardly, and suction means positively progressing the sheet while so bent as it is delivered from the table.

21. A sheet delivery mechanism including in combination a delivery table, means for bending the sheet transversely and upwardly and outwardly, and suction means on its under side positively progressing the sheet while so bent as it is delivered from the table.

22. A sheet delivery mechanism including in combination a delivery table, and means engaging only the unprinted side of the sheet adapted to bend the sheet transversely as it is delivered from the table.

23. A sheet delivering and stacking mechanism including in combination sheet stacking means, and suction means for delivering a sheet to the stack and devices for curving the sheet transversely upwardly, the suction means keeping control of the sheet until it is entirely delivered.

24. A sheet delivering and stacking mechanism including in combination sheet stacking means, and delivery means including suction devices for delivering a sheet to the stack, and devices for bending the sheet transversely, said stacking means causing the sheet to bend transversely downwardly when deposited on the stack.

25. A sheet delivery mechanism including in combination a multi-part sheet delivery table, the forward part thereof being longitudinally reciprocably movable relatively to the rear part thereof and means for progressing a sheet along the table.

26. A sheet delivery mechanism including in combination a multi-part sheet delivery table, the forward part thereof being longitudinally reciprocably movable relatively to the rear part thereof, and a forward portion of the table being hinged, and means for progressing a sheet along the table.

27. A sheet delivery mechanism including in combination a delivery table, and a plurality of suction means adapted to engage the underside of a sheet and move it along the table, said suction means being located lengthwise of the table with their adjacent ends overlapping.

28. A sheet delivery mechanism including in combination a delivery table, a plurality of belts adapted to engage the underside of a sheet and arranged longitudinally of the table with their adjacent ends overlapping,

and suction means coacting with the belts to cause the sheets to move with the belts.

29. A sheet delivery mechanism including in combination a main delivery table, a front

5 delivery table inclined relatively thereto, and suction means on the front and rear tables adapted to engage a sheet and continuously progress it along and over both tables.

10 30. A sheet delivery mechanism including in combination a delivery table, means for moving the sheet over said table, and means engaging the underside of the sheet to bend it transversely as it is projected from the table.

15 31. A sheet delivery mechanism including in combination a delivery table, means for moving the sheet over said table, and means engaging the underside of the sheet for bending it transversely upwardly and outwardly as it is projected from the table.

20 32. A sheet delivery mechanism including in combination a delivery table, suction means for moving the sheet over the table, and means for bowing the central portion of 25 the sheet upwardly as it is delivered from the table.

33. A sheet delivering and stacking mechanism comprising in combination sheet

stacking means, sheet delivery means including suction devices for moving the sheet, and devices for bowing the sheet as it is delivered to the stack.

34. A sheet delivery mechanism including in combination a delivery table and a 35 plurality of narrow suction means mounted on the table and adapted to successively engage the lower side of a sheet and move it along the table.

35. A sheet delivery mechanism including in combination a delivery table, a plurality of narrow belts mounted on the table and adapted to successively engage the underside of a sheet, and suction means coacting with the belts to cause the sheet to 40 adhere to the belts and be moved thereby along the table.

36. A sheet delivery mechanism including in combination a delivery table, a plurality of narrow belts on the table adapted to 50 successively engage the underside of a sheet, and a suction chamber extending along and beneath the belts and coacting with the belts to cause the sheet to adhere to the belts and be moved thereby along the table. 55

In testimony whereof, I have signed my name to this specification.

MICHAEL A. DROITCOUR.
